Primary Examiner — T Chase Nelson*Assistant Examiner* — Jonathan J. Han(74) *Attorney, Agent, or Firm* — Fishman Stewart PLLC(57) **CLAIM**

The ornamental design for a vessel, as shown and described.

DESCRIPTION

FIG. 1 is a perspective view of a vessel of the present design; FIG. 2 is another perspective view of the vessel of FIG. 1; FIG. 3 is a top view of the vessel of FIG. 1;

FIG. 4 is a bottom view of the vessel of FIG. 1;

FIG. 5 is a rear view of the vessel of FIG. 1;

FIG. 6 is a front view of the vessel of FIG. 1; and,

FIG. 7 is a side view of the vessel of FIG. 1.

Portions in FIGS. 1–7 that are shown with broken lines depict unclaimed subject matter and are for illustrative purposes only, forming no part of the claimed design.

1 Claim, 4 Drawing Sheets(56)
